OPENING MEANS FOR REGULAR CARTONS

Robert M. Dunning, St. Paul, Minn., assignor to
Waldorf Paper Products Company, St. Paul,
Minn., a corporation of Minnesota

Application August 21, 1947, Serial No. 769,798

8 Claims. (Cl. 229—17)

1

My invention relates to an improvement in opening means for regular cartons wherein it is desired to provide an easy operable means of opening a carton to dispense the contents thereof.

It is an object of the present invention to provide a corner of the carton with a flap which may be quickly and easily opened to permit the contents of the package to be poured from this corner. Thus the corner of the carton forms a pouring spout through which the package contents may be poured.

A feature of the present invention lies in the provision of a tab of generally triangular shape having a projecting portion extending beyond the fold line connecting the triangular tab to the remainder of the carton. By pressing on the projecting portion, the triangular tab may be hinged about its line of fold to produce a triangular opening at one corner of the package.

A feature of the present invention lies in the provision of an opening tab which extends on both sides of aligned lines of fold connecting the tab to the remainder of the carton. Thus by depressing one portion of the tab into the carton the opposite end of the tab may be raised to permit pouring from the package.

An added feature of the present invention lies in the provision of a tab extending on both sides of a fold line connecting the tab to the carton and in producing this tab in a plurality of laminations of carbon stock. Thus the tab when formed is of several thicknesses of carton stock, adding materially to the strength of the tab and reinforcing the body thereof.

An added feature of the present invention lies in the provision of a tab which is defined on one end by a pair of diverging weakened lines of separation along which the tab may be separated from the remainder of the carton. The other end of the tab is formed of a plurality of thicknesses of carton stock, the layers of stock being of different size so that this tab end is not defined along a cut line extending entirely through the carton. This end of the tab is of stepped formation about its periphery and is accommodated in a carton wall of similarly stepped formation to provide adequate closure when the flap is closed.

An added feature of the present invention lies in the fact that my carton closure may be formed in a carton of the common sealed end type. By producing proper cut lines, fold lines, and perforated lines in the carton stock my closure may be produced without adding any carton stock.

These and other objects and novel features

2

of my invention will be more clearly and fully set forth in the following specification and claims.

In the drawings forming a part of my specification:

Figure 1 is a perspective view of my carton in closed form.

Figure 2 is an enlarged view showing a portion of the top of the carton and showing the closure in partially opened position.

Figure 3 is a diagrammatic view of the major portion of the blank from which the carton is formed.

Figure 4 is a sectional view through a corner of the carton and the closure therefor.

The carton A may be of any usual type or description having four walls hingedly connected together along lines of fold and connected in tubular relation. A carton of the usual glued end type is illustrated in Figure 3, the lower edge of the blank being omitted if conventional folding flaps are used at this end. The carton A as illustrated includes wall panels 10, 11, 12 and 13 foldably connected together along parallel fold lines 14, 15, and 16. The glue flap 17 is hingedly connected to one end panel of the series, such as the panel 13 by a fold line 19.

The panels 10, 11, 12 and 13 are connected along a common line of fold 20 to the various top closure flaps. A closure flap 21 is hingedly connected to the panel 10. A closure flap 22 is hingedly connected to the flap 11. A closure flap 23 is hingedly connected to the flap 12 while a flap 24 is hingedly connected to the panel 13.

As the flaps 21 and 23 are usually folded into coplanar relationship inwardly of the flaps 24 and 25, these flaps will first be described. The flap 21 is a conventional type of flap which when folded inwardly, will extend toward the center of the carton and underlie the flaps 22 and 24. The flap 23 comprises a triangular area 25, an integral flap portion 26, and a remaining flap portion 27. The generally triangular area 25 is bounded on one side by the cut line 29 separating the flaps 22 and 23. Along a second edge the triangular area 25 is bounded by a perforated line 30 which extends along the fold line 20. The third side of the triangular area is bounded by the cut line 31 and the aligned cut score line or perforated line 32. The flap 23 is weakened sufficiently along the line 30 so that the flap will split or tear along this line when the closure is first opened.

The flap portion 26 is generally rectangular in area and includes a cut line 33 along one edge,

a cut line 34 along a second edge, and a cut score or perforated line 35 along a third edge. The fourth edge of the generally rectangular tab portion 26 is integral with the triangular area 25. Thus the tab portions 25 and 26 form in effect an arrowhead shaped member which outlines the tab or openable part of the closure.

The area 27 of the flap 23 is bounded by the cut score or perforated line 35, an extension of the cut line 34, the cut line 36 between the flaps 23 and 25, the fold line 20, and the cut score or perforated line 32. It will be noted that the marginal edge of the flap portion 26 is printed or coated as indicated by the shade lines 37 so that the adhesive adhering the various flaps together will not adhere along these lines. As a result the various layers forming the tab will adhere together, but the plies will remain unattached along the rabbeted edge of the tab.

The flap 22 is provided with a tab portion therein which is similar in shape to the tab portions 25 and 26 of the flap 23. The flap 39 in the flap 22 includes a triangular area 40 and an integral rectangular area 41. The triangular area 43 is bounded on one edge by the cut line 29 and on a second edge by a perforated line 42 along the fold line 20. The third edge of the triangular area is partially bounded by a pair of aligned cut lines 43 and 44. These cut lines 43 and 44 may if desired comprise perforated lines, cut score lines, or even fold lines, but it is preferable that the tab separate from the remainder of the flap 22 if the tab is opened into the position shown in Figure 2 so that the hinge may be formed in a single thickness of carton stock.

The rectangular area 41 of the tab 39 is defined along three edges by a U-shaped cut line 45 which terminates in alignment with the cut lines 43 and 44. The rectangular area 41 is printed or coated marginally as indicated at 46 so that the adhesive between flaps 22 and 24 will not adhere the marginal edges of the rectangular area 41 to the flap 24. Thus an arrowhead shaped tab 39 is formed in the flap 22 which is similar in shape to the tab in the flap 23 except that the rectangular areas are of different size.

The flap 24 is provided with a tab 47 which is also in the general shape of an arrowhead and which is designed to overlie the tabs previously described when the carton is closed. The tab 47 includes a generally triangular area 49 and a generally rectangular area 50 integrally connected together. The triangular area 49 is defined along one edge by the cut line 36 and along a second edge by the free edge 51 of the flap 24. The third side of the triangular area is partially defined by a pair of aligned fold lines 52 and 53. The rectangular area 50 is defined by a U-shaped cut line 54 which terminates at its open end in alignment with the fold lines 52 and 53.

In the folding of the carton the flap 23 is folded into coplanar relation with the flap 21. The flap 22 is folded to overlie the flap 23 and the flap 24 is folded to overlie the flap 22. It will be noted that the triangular areas of the three flaps are of substantially equal size and the fold lines 52 and 53 overlie the cut lines or fold lines of the triangular areas beneath. It should also be noted that the flap 47 is provided with a rectangular projecting tab portion of relatively small area; the flap 39 has a rectangular area of somewhat larger dimension, and the rectangular area 26 of the flap 23 has still larger dimensions. As a result the cut lines encircling the three rectangular areas do not coincide and as a result a

rabbeted edge is provided about these tabs. The adhesive securing the flap 22 to the flap 23 and securing the flap 24 to the flap 22 does not connect the layers together along this rabbeted edge, thereby permitting the rectangular areas of the tab to be forced down into the interior of the carton. By forming the lowermost tab larger than the tabs above also permits certain irregularities in folding and does not require that the various layers be in perfect regular form in order to operate.

In opening the carton, the carton is torn or cut along the perforated lines 30 and 42 to separate the triangular areas of the tabs from the adjacent side walls of the carton. The tab may then be opened by pressing upon the rectangular area 50 of the uppermost tab 47, this action causing the tab to hinge along the fold lines 52 and 53 as illustrated in Figure 2 of the drawings. As the tabs swing into open position, it is desirable that the tabs forming the lowermost two layers tear along the lines of fold so as to simplify the folding of the tab and allow the tab to be folded in either direction with a minimum of ease.

In accordance with the patent statutes, I have described the principles of construction and operation of my opening means for regular cartons, and while I have endeavored to set forth the best embodiment thereof, I desire to have it understood that obvious changes may be made within the scope of the following claims without departing from the spirit of my invention.

I claim:

1. An opening means for a carton having side walls connected in tubular relation and a top closure comprising a series of laminations, said opening means including a triangular tab portion forming a part of said closure, two sides of said triangular tab portion being defined by adjacent sides of said top closure, the third side of said triangular portion being partially defined by a pair of spaced aligned fold lines, and a tab portion on said triangular tab portion extending on the opposite side of said fold lines from said triangular tab portion and connecting the spaced ends of said aligned fold lines, said last named tab portion being foldable to one side the plane of said closure when the triangular portion folds to the other side of the plane of said closure.

2. An opening means for a carton having side walls connected in tubular relation and a top closure comprising a series of laminations, said opening means including a triangular tab portion forming a part of said closure, two sides of said triangular tab portion being defined by adjacent sides of said top closure, the third side of said triangular portion being partially defined by a pair of spaced aligned fold lines, and a tab portion on said triangular tab portions extending on the opposite side of said fold lines from said triangular tab portion and connecting the spaced ends of said aligned fold lines, said last named tab portion being foldable to one side of the plane of said closure when the triangular portion folds to the other side of the plane of said closure, the two sides of said triangular closure portion being defined by the adjacent edges of said closure being connected to the adjacent walls of the carton along weakened lines of separation.

3. An opening means for a carton having side walls connected in tubular relation and a top closure comprising a series of laminations, said openings means including a triangular tab portion forming a part of said closure, two sides of said triangular tab portion being defined by

adjacent sides of said top closure, the third side of said triangular portion being partially defined by a pair of spaced aligned fold lines, and a tab portion on said triangular tab portion extending on the opposite side of said fold lines from said triangular tab portion and connecting the spaced ends of said aligned fold lines, said last named tab portion being foldable to one side of the plane of said closure when the triangular portion folds to the other side of the plane of said closure, said last named tab portion being formed with a stepped marginal edge.

4. An opening means for a carton having side walls connected in tubular relation and a top closure comprising a series of laminations, said opening means including a triangular tab portion forming a part of said closure, two sides of said triangular tab portion being defined by adjacent sides of said top closure, the third side of said triangular portion being partially defined by a pair of spaced aligned fold lines, and a tab portion on said triangular tab portion extending on the opposite side of said fold lines from said triangular tab portion and connecting the spaced ends of said aligned fold lines, said last named tab portions being foldable to one side of the plane of said closure when the triangular portion folds to the upper side of the plane of closure, said tab being formed of a plurality of thicknesses of carton stock.

5. An opening means for a carton having rectangularly arranged side walls and closure flaps thereon folded into superimposed relation, the opening means comprising a tab formed in said closure, said tab including a triangular portion being defined by two adjacent edges of the closure and a diagonal line connecting said adjacent edges, said tab also including an operating portion projecting beyond said diagonal line and being defined by a cut line of generally U-shape terminating at the diagonal, and aligned fold lines between the ends of said U-shaped cut line and adjacent edges.

6. An opening means for a carton having rectangularly arranged side walls and closure flaps thereon folded into superimposed relation, the opening means comprising a tab formed in said closure, said tab including a triangular portion being defined by two adjacent edges of the closure and a diagonal line connecting said adjacent edges, said tab also including an operating portion projecting beyond said diagonal line and being defined by a cut line of generally U-shape terminating at the diagonal, and fold lines on said diagonal line between the ends of said

U-shaped cut line and said adjacent edges, said tab being formed in a plurality of said closing flaps, thus being formed of a plurality of layers.

7. An opening means for a carton having 5 rectangularly arranged side walls and closure flaps thereon folded into superimposed relation, the opening means comprising a tab formed in said closure, said tab including a triangular portion being defined by two adjacent edges of the closure and a diagonal line connecting said adjacent edges, said tab also including an operating portion projecting beyond said diagonal line and being defined by a cut line of generally U-shape terminating at the diagonal, and fold lines on 10 said diagonal line between the ends of said U-shaped cut line and said adjacent edges, said tab being formed in a plurality of said closing flaps, thus being formed of a plurality of layers, the U-shaped cut lines of each layer defining a larger area than the U-shaped cut line of the next 15 layer thereabove.

8. An opening means for a carton having rectangularly arranged side walls and closure flaps thereon folded into superimposed relation, the 20 opening means comprising a tab formed in said closure, said tab including a triangular portion being defined by two adjacent edges of the closure and a diagonal line connecting said adjacent edges, said tab also including an operating portion projecting beyond said diagonal line and being defined by a cut line of generally U-shape terminating at the diagonal, and fold lines on 25 said diagonal line between the ends of said U-shaped cut line and said adjacent edges, said tab being formed in a plurality of said closing flaps, thus being formed of a plurality of layers, the U-shaped cut line defining the lowermost layer defining a larger area than the U-shaped cut line of the tab thereover, and ink repelling means 30 on the marginal edge of the lowermost layer adjacent said U-shaped cut line.
